DESIGN FOR ILLUMINATED ELECTRIC SHAVER

Charles W. Bailey, Denver, Colo.

Application December 16, 1938, Serial No. 81,810

Term of patent 7 years

To whom it may concern:

Be it known that I, Charles W. Bailey, a citizen of the United States, residing at Denver, in the county of Denver and State of Colorado, have invented a new, original, and ornamental Design for Illuminated Electric Shaver, of which the following is a specification, reference being had to the accompanying drawing, forming part thereof.

Figure 1 is a side view of an illuminated electric shaver, namely, a view looking in the direction indicated by arrows designated as 1 in Figs. 2 and 3.

Figure 2 is an edge view of same, namely a view looking in the direction indicated by arrows designated as 2 in Figs. 1 and 3.

Figure 3 is a view looking into the operating end of the shaver, namely in the direction indicated by arrows 3 in Figs. 1 and 2.

I claim:

The ornamental design for illuminated electric shaver, as shown.

CHARLES W. BAILEY.
